238,285

GOLF CLUB HEAD

Barney F. Ross, 3302 St. Albans Drive,
Los Alamitos, Calif. 90720

Filed June 3, 1974, Ser. No. 475,407

Term of patent 14 years

Int. Cl. D21—02

U.S. Cl. D34—5 GH

FIG. 1 is a perspective view of a golf club head embodying my invention;

FIG. 2 is a plan view looking at the top of the club;

FIG. 3 is an elevation view looking at the front side of the club;

FIG. 4 is a view of the bottom of the club;

FIG. 5 is an elevation view looking at the toe of the club;

FIG. 6 is an elevation view looking at the heel of the club;

FIG. 7 is an elevation view looking at the heel of the club;

FIG. 8 is a section taken on lines 8—8 of FIG. 3;

FIG. 9 is a section taken on lines 9—9 of FIG. 7.

I claim:

The ornamental design for a golf club head, as shown.
